UNITED STATES PATENT OFFICE.

CHARLES L. DAVIS, OF DETROIT, MICHIGAN, ASSIGNEE TO UNDERWOOD TYPEWRITER COMPANY, OF NEW YORK, N. Y., A CORPORATION OF DELAWARE.

AUTOMATIC TYPE-WRITER OPERATOR.

1,099,895.

Specification of Letters Patent

Patented June 9, 1914.

Application filed September 7, 1912. Serial No. 719,057.

To all whom it may concern:

Be it known that I, CHARLES L. DAVIS, a citizen of the United States, residing in Detroit, in the county of Wayne and State of Michigan, have invented certain new and useful Improvements in Automatic Type-Writer Operators, of which the following is a specification.

This invention relates to a fair-leading mechanism for justifying the position of a master sheet with respect to its tracker board.

In the use of a master sheet in connection with a tracker board, as in controlling the actuation of typewriter operating mechanism, it often happens that the master sheet slips to one side or the other, bringing the apertures in the master sheet out of register with the corresponding apertures in the tracker board. Such a mishap would interfere with the proper action of the machine.

It is therefore an object of this invention to cause any disaligning movement of the master sheet to correct itself and at a point 25 in advance of the tracker board, so that the position of the master sheet will be justified when it reaches the tracker board, thereby bringing the accordant apertures into proper register with each other.

In a master sheet for controlling the actions of an automatic operator for a typewriter to which this invention is shown as applied, there are provided a series of apertures for controlling the action of the space key of the typewriter, which may be termed the space key apertures. Inasmuch as the space key is operated after each word, these apertures occur frequently, and in fact, sufficiently often to form a substantial line of 35 apertures. This line of space key apertures is used in connection with a special justifying tracker board for controlling the lead of the master sheet to the main tracker board. The justifying tracker board, which is located in advance of the main tracker board, is provided with a pair of parallel slits of sufficient length to practically always have one or more of the space key apertures in their scope of action. The slits are spaced 45 apart from each other by a solid strip just such a sufficient distance that when the

master sheet is in its true position, the space key apertures will be in register with the solid strip and overlapping neither of the slits. The slits under such conditions are 55 covered and closed by the solid portions of the master sheet. If the master sheet slips out of true alignment to either one side or the other, then air is admitted through one of the space key apertures to the corresponding slit, which is connected to carry the air to the associated side of a normally balanced pneumatic actuator, thereby causing the swing of the actuator to this side. The actuator moves a fair-lead guide, which 65 is in engagement with the master sheet in advance of the main tracker board, so that the master sheet is shifted back to correct the disalignment.

Other features and advantages will hereinafter appear.

In the accompanying drawings, Figure 1 is a rear view in elevation, partly broken away to show the underlying structure. Fig. 2 is a fragmentary view in elevation, 75 taken at right angles to the view shown in Fig. 1. Fig. 3 is a fragmentary perspective view of the special or justifying tracker board, partly broken away to show the underlying structure.

Referring more particularly to the separate parts of this invention as embodied in the form shown in the drawings, 1 indicates a master sheet which is provided with a plurality of apertures 2 cut therein according to a predetermined arrangement to correspond to the operation of some extraneous mechanism, such as an operator for a typewriter, to obtain a predetermined sequence of operation of the parts of the typewriter. 85 Such a typewriter operator is shown in the application of Lyman R. Roberts and Charles L. Davis, No. 428,050, filed April 20, 1908. The master sheet 1 is supported by one or more rollers 3 and 4 in such a 95 manner that it will be drawn snugly over the face of a main tracker board 5. Either one or both of the rollers 3 and 4, or some other means, may be used to drive the master sheet. The tracker board 5 is provided 100 with a series of apertures 6 which are connected by pipes 7 to individual pneumatic

actuators (not shown) for operating distinct parts. The action is such that when one of the apertures in the master sheet 1 comes in register with one of the apertures 5 in the tracker board 5, air will be admitted to the pipe 7, so that the particular associated pneumatic actuator is brought into activity. It will be seen that in order to have a positive and correct action, the apertures 2 must 10 properly register with the accordant apertures 6.

In order to detect any errors in register before they reach the main tracker board 5, there is provided a special justifying tracker board 8, which is located in advance of the main tracker board 5. This special tracker board 8 not only detects the errors, but enables the correction of the errors in alignment, so that any improper adjustment of the 20 master sheet 1 will be rectified before such errors can come to the main tracker board 5. For this purpose use is made of certain of the apertures 2 in the master sheet 1. In this case the space key apertures indicated 25 at 9 are used inasmuch as they occur at points corresponding to the spaces between successive words, which spaces are quite frequent. These space key apertures 9 form a substantial row of openings in the master 30 sheet 1 and are arranged to coöperate with a pair of slits 10 and 11 forming the inlets of cavities in the tracker board 8. These slits 10 and 11 are spaced apart from each other by a solid bridge 12 just such a distance, 35 that when the master sheet is in its true position, the space key apertures 9 will travel over the bridge 12, and will not overlap either of the slits 10 or 11; that is to say, the blank or solid portion of the master 40 sheet will cover the slits 10 and 11 so as to prevent the passage of air into the cavities for which they form inlets. The slits 10 and 11 are connected by conduits 13 and 14, shown in the form of rubber tubes, to opposed units 15 and 16 of a pneumatic actuator 45 17. The units 15 and 16 are shown in the form of collapsible bellows arranged on opposite sides of a fixed block 18 and connected to the pipes 13 and 14 by means of 50 passages 19 and 20 in the block 18. The outer ends of the bellows are connected together in any suitable manner, as by means of a link 21 pivotally connected to lugs 22 and 23 on the units 15 and 16 so that they 55 will move in unison in the same direction. Under normal conditions the units 15 and 16 are held in balanced relation by means of a suction from any suitable source indicated by the conduit or pipe 24 which lets 60 into a passage 25 common to both of the units 15 and 16. The mouths of the passage 25 are normally closed by valves 26 and 27 of any suitable character such that, however, the opening will be rather small, and

such that when air pressure enters one of the 65 units, it will render this opening or passage smaller still by pressing the flexible valve against the block 18. Any movement started in either one or the other of the units 15 and 16 will be transmitted by a link 28 to a lever 29 which has a connection at its opposite end with an annularly grooved collar such that it will permit a rotation of the collar, but will transmit a transverse movement to the collar. The collar 30 is secured 75 to a fair lead guide 31, which is shown in the form of a rotatable rod having flanges 32 thereon adapted to engage opposite edges of the master sheet 1. The rod is mounted at its ends in bearings 33 and 34 in such a manner that it can rotate and can also slide in the direction of its length to shift the position of the master sheet 1.

In the use of the device, the master sheet 1 is fed by any suitable driving means, which 85 may be represented by roller 3, so that it passes by the face of the main tracker board 5, bringing the apertures therein into individual register with the accordant apertures on the tracker board 5, thereby controlling 90 the action of certain pneumatic mechanism. If the master sheet 1 should slip to one side or the other tending to bring the apertures 2 out of proper alinement with their accordant apertures 6, this maladjustment would 95 be detected immediately by the tracker board 8. If, for example, the master sheet 1 slipped to the right in Fig. 1, one or more of the space key apertures 9 would be brought 100 into register with the slit 11, so that air would be admitted through the pipe 14 to the unit 16 of the pneumatic actuator 17. When thus admitted, the air will almost close the valve 27, so that the balance of the pneumatic actuator will be disturbed inasmuch as there is suction on the unit 15 and atmospheric pressure on the unit 16. This 105 would cause the elements of the pneumatic actuator including the link 21 to move to the right (in Fig. 1), thereby rocking the lever 110 to shift fair-lead guide 31 to the left, thereby forcing the master sheet 1 also to the left bringing the apertures 9 once more in 115 superposed relation with respect to the bridge 12 and out of register with the slit 11. If the master sheet slipped to the left, a similar action would take place, only that the unit 15 would have air admitted to it, causing a movement of the elements of the pneumatic actuator to the left and a corresponding movement of the fair lead guide 120 31 to the right.

The valves 26 and 27 do not form such an air-tight closure when the slits 10 and 11 are once more covered but what the air can be 125 drawn out of the particular unit which was in action, enabling the shift to the opposite direction. The pneumatic actuator and the

fair lead guide taken together may be termed a shifter for obtaining a proper register of the apertures in the master sheet with the apertures in the tracker board.

5 Variations may be resorted to within the scope of the invention, and portions of the improvements may be used without others.

Having thus described my invention, I claim:

10 1. The combination with a main tracker board, of a master sheet coöperating with said tracker board to control the action of some mechanism, means for attaining a relative movement between said tracker board and said master sheet, and a special tracker board placed in advance of said main tracker board to discover errors in placement of said master sheet before reaching the main tracker board, said special tracker board controlling said means to obtain a proper register of said master sheet and said main tracker board.

25 2. The combination with a main tracker board, of a master sheet coöperating with said tracker board to control the action of some mechanism, a special tracker board placed in advance of said main tracker board to discover errors in placement of said master sheet before they reach said main tracker board, and means controlled by said special tracker board engaging said master sheet in advance of said main tracker board to shift said sheet to correct errors in placement before they come to said main tracker

35 3. The combination with a tracker board having apertures therein, of a master sheet coöperating with said tracker board and having apertures for controlling the actuation of distinct parts of a mechanism, and means for also utilizing certain of said apertures in said master sheet for the additional purpose of controlling the proper register of the apertures in said master sheet with the

45 apertures in said tracker board.

4. The combination with a tracker board, of a master sheet coöperating with said tracker board to control the actuation of parts of a typewriter, said master sheet having a series of space key apertures corresponding to the actuation of the space key of the typewriter, and means controlled by said space key apertures to govern the relative transverse relation of said tracker board and said master sheet.

5. The combination with a main tracker board, of a master sheet coöperating with said tracker board to control the actuation of parts of a typewriter, said master sheet having a plurality of controlling apertures therein, a justifying tracker board in advance of the main tracker board and having a pair of slits therein located at the distance of the width of an aperture from each

other, and a shifter for moving said master sheet when one of said apertures comes in register with one of said slits.

6. The combination with a main tracker board, of a master sheet coöperating with said tracker board to control the action of some mechanism, a special tracker board placed in advance of said main tracker board to discover errors in placement of said master sheet before they reach said main tracker board, and means controlled by said special tracker board engaging said master sheet in advance of said main tracker board and in advance of said special tracker board to shift said master sheet to correct errors in placement before reaching the said special tracker board and said main tracker board.

7. The combination with a main tracker board, of a master sheet coöperating with said tracker board to control the actuation of some mechanism, rollers for carrying said master sheet, a fair lead guide engaging said master sheet at a point in advance of the tracker board, an actuator for manipulating said guide, and means dependent on the position of said master sheet for controlling said actuator, and operating the guide to rectify errors in the lateral position of the master sheet in advance of its engagement with the tracker board.

8. The combination with a tracker board having apertures therein, of a master sheet having apertures therein and arranged to coöperate with said tracker board to control the actuation of some mechanism, and means for detecting and correcting registration of the apertures in said master sheet with the accordant apertures in said tracker board in advance of said tracker board, so that the proper register of the accordant apertures will be obtained at the tracker board.

9. The combination with a tracker board having an elongated aperture therein, of a master sheet having a series of apertures which move in close proximity to said elongated aperture during the normal travel of the master sheet, said apertures being so arranged that at least one aperture is always in position to become operative with said elongated aperture, a guide for the master sheet, and a pneumatic device for shifting said guide, said device communicating with said apertures whereby lateral displacement of the master sheet establishes communication between the apertures of said series and said elongated aperture and said guide is shifted to restore the master sheet to its normal path of travel.

10. The combination with a tracker board having parallel elongated apertures, of a master sheet having a series of apertures to pass between said elongated apertures when the master sheet is fed forward in its normal path, said elongated apertures being of such

length as to permit more than one aperture of said series therebetween, a device for guiding the master sheet and shifting it laterally, and pneumatic means in communication with said elongated openings of said series are brought in communication with said elongated openings.

5

3

guiding the master sheet and shifting it laterally, and pneumatic means in communication with said elongated openings to shift said guide and thereby return the master sheet to its normal path of travel when the
